UNITED STATES PATENT OFFICE.

MARION W. McCANN, OF HENRY, INDIANA.

CAR-COUPING.

SPECIFICATION forming part of Letters Patent No. 230,796, dated August 3, 1880.

Application filed June 4, 1880. (No model.)

To all whom it may concern:

Be it known that I, MARION W. McCANN, of Henry, in the county of Henry and State of Indiana, have invented certain new and useful

5 Improvements in Car-Couplers; and I do hereby declare that the following is a full, clear, and exact description thereof, reference being had to the accompanying drawings, and to the letters of reference marked thereon, which form part of this specification, in which—

10 Figure 1 is an end view of a car, showing my coupling in position; Fig. 2, a similar view, showing the coupling-pin raised; and Fig. 3, a longitudinal section through the draw-bar.

15 The object of my invention is to furnish an effective and economical means for coupling and uncoupling railroad-cars; and to this end it consists in the combination and arrangement of certain devices, which will be hereinafter 20 more fully described, and specifically set forth in the claims.

To enable others skilled in the art to which my invention pertains to make and use the same, I will now proceed to describe its construction and arrangement.

25 A represents a car-body, which is provided with draw-bar B and bumpers C C. The draw-bar is furnished with spiral spring a and plug or block b, which is stepped or notched at its 30 forward under side, as fully shown in Fig. 3.

35 e represents a stop-bolt, which extends from side to side of the draw-bar, just back of its mouth, for the purpose of preventing the plug b from being pushed entirely out by the spring.

30 f f and short standards or lugs g g on the bumpers, as seen in Figs. 1 and 2.

40 h h are rods which connect the levers, and by means of which the coupling-pins may be operated.

45 K represent springs, whose outer ends are secured to the bumpers, and whose inner ends are bent backward to form a slot through which

the pivot-bolt connecting the levers e e and coupling-pin d passes. The object of these springs is to force the pin down quickly when the plug b is pushed back by the link.

50 m represents a vertical rod, whose lower end is secured to one of the levers e e, and whose upper end is provided with handle O, thus enabling a man from the top of the car to disconnect or uncouple them when desired.

55 In operation, the pin is raised by means of the levers or rod from the sides or top of the car, and the block or plug b is forced by its spring under the pin, holding it up. The other car, with the link in position, being now backed 60 up, the link will strike the notch or step in the block b and force said block back, releasing the pin d, which is quickly dropped through the draw-head and link by the action of the springs K K.

65 Having thus fully described my invention, what I claim as new, and desire to secure by Letters Patent, is—

1. The combination, with coupling-pin d, of the levers e e, pivoted thereto and provided 70 with spring or springs for forcing the pin quickly in position to couple the cars, substantially in the manner herein set forth.

2. The combination, in a car-coupler, of the pin d, levers e and f, connecting-rods h h, and 75 springs K, all constructed and arranged to operate substantially as and for the purpose described.

3. The combination, in a car-coupling, of levers e and f, connecting-rods h h, springs K, 80 pin d, plug b, spring a, stop-bolt e, and draw-head B, all constructed and arranged to operate substantially as and for the purpose specified.

85 In testimony that I claim the foregoing as my own invention I affix my signature in presence of two witnesses.

MARION W. McCANN.
